UNITED STATES PATENT OFFICE.

WILLARD F. RICHARDS, OF DEPEW, NEW YORK, ASSIGNOR TO GOULD COUPLER COMPANY, OF NEW YORK, N. Y.

CENTERING AND SUPPORTING DEVICE FOR CAR-COUPINGS.

1,236,873.

Specification of Letters Patent. Patented Aug. 14, 1917.

Application filed March 17, 1916. Serial No. 84,814.

To all whom it may concern:

Be it known that I, WILLARD F. RICHARDS, a citizen of the United States, residing at Depew, in the county of Erie and State of New York, have invented a new and useful Improvement in Centering and Supporting Devices for Car-Couplings, of which the following is a specification.

This invention relates to centering and supporting devices which are used in conjunction with the couplers of cars or other railway rolling stock for the purpose of permitting the couplers to swing or move sidewise when the cars are rounding curves and returning the couplers to and yieldingly holding them in their normal central positions.

The objects of the invention are to provide a simple, strong and durable centering and supporting device of this sort which is so constructed that a relatively great movement of the coupler to both sides of its central position is permitted while the device is nevertheless short and the centering mechanism does not project or move in the operation thereof substantially beyond the ends of the drawbar support or carry iron; and also to improve the construction of devices of this kind in the respects hereinafter described and set forth in the claims.

In the accompanying drawings:

Figure 1 is a plan view of a coupler and supporting and centering device therefor embodying the invention.

Fig. 2 is a similar view showing the coupler swung to one side.

Figs. 3 and 4 are transverse sectional elevations thereof, on an enlarged scale, on lines 3—3, Fig. 1, and line 4—4, Fig. 2, respectively.

Fig. 5 is a longitudinal sectional elevation thereof, on line 5—5, Fig. 4.

Fig. 6 is a side elevation thereof.

A represents a coupler and a the shank or drawbar thereof, which is pivoted at its inner end at a' to permit the coupler to swing sidewise to either side of the normal central position shown in Fig. 1. The coupler and drawbar may be of any usual or desired construction and may be pivoted or movably connected to the car or other railway rolling stock in any suitable manner.

B represents a carry-iron or support for the outer end of the drawbar. This carry-

iron, as usual, has upright end attaching portions b with laterally projecting upper ends adapted to be bolted or otherwise secured to the car or other rolling stock, and a horizontal portion b' which connects the lower ends of the attaching portions beneath the drawbar, which is supported thereby. The carry-iron B preferably consists of a single-piece steel casting, the connecting portion of which is in the form of an open-ended hollow cylinder or tubular spring housing having a substantially flat horizontal top face b². C represents a saddle or slide in which the drawbar rests and which is adapted to slide with the drawbar on the carry-iron B between the end attaching portions b thereof. This saddle preferably consists of a single-piece substantially U-shaped metal part having a horizontal bottom and upwardly projecting sides c between which the drawbar is confined, said sides c having convexed inner surfaces, as shown in Figs. 1 and 2, on which the drawbar is adapted to rock and slide in the horizontal swinging movements of the drawbar. The saddle rests and is adapted to slide on the horizontal top of the spring housing b' of the carry-iron.

Extending lengthwise in the spring housing b' is a coil spring D which bears at its ends against abutments or followers F F' arranged to slide longitudinally in the housing. These sliding abutments are preferably in the form of cylindrical sockets or sleeves in which the ends of the spring are confined. The saddle is provided at opposite ends with parts d d' respectively adapted to engage co-operating parts f f' at the inner ends of the sleeves F F', whereby one sleeve is moved by the saddle when the drawbar swings to one side from its central position, and the other sleeve is moved by the saddle when the drawbar swings to the other side from its central position. Preferably the parts d d' consist of lugs depending from the end portions of the saddle into a longitudinal slot d² in the top wall of the spring housing b', and the parts f f' consist of lugs projecting up from the inner ends of the sleeves F F' into the slot d² in the path of the saddle lugs. The saddle lugs d d' guide the saddle in its movements and these lugs and the lugs on the sleeves are preferably provided with undercut or inclined

faces f^2 which coöperate to prevent the saddle from lifting out of place on the carry-iron.

- The spring and sliding spring sleeves are retained in the spring housing by end caps G which are secured in place on the ends of the housing by a bolt or rod H which extends lengthwise centrally through the spring housing and through the caps G.
- 5 The slot d^2 in the spring housing is preferably continued through the upright end portions b of the carry-iron, and the caps G are cut away or flattened at g opposite the slot so that any cinders or other matter which 10 may fall into the slot will be shoved out of the open ends thereof by the lugs d d' of the saddle in the operation of the centering device and will not collect in the housing or interfere with the movement of the saddle.
- 15 20 The caps can be prevented from turning on the housing so as to retain their flat edges g in register with the slot d^2 by the engagement of the edges g with shoulders g' on the ends of the housing, or in any other convenient way. The bolt or rod H passes loosely through the spring sleeves and spring and is provided with a head at one end engaging one cap G and with one or more nuts h at the other end engaging the other cap.
- 25 30 Normally the spring D holds the spring sleeves F F' apart in the outer ends of the spring housing against the end caps G, and holds the lugs f f' of the sleeves in contact with the inner faces of the lugs d d' on the saddle, thereby retaining the saddle and drawbar in the central position, as shown in Fig. 3. When the drawbar is moved in one direction, for instance to the right, as shown in Fig. 4, the saddle will be moved correspondingly and the lug d of the saddle, by its engagement with the lug f of the left-hand sleeve F, will draw this sleeve inwardly and compress the spring D against the other sleeve F' which is then held from movement against the adjacent cap G. The spring will return the saddle and drawbar to the central position when the side pressure on the drawbar is released. In a similar manner, when the drawbar and saddle are moved in the opposite direction from the central position the right-hand sleeve F' will be drawn inwardly by the engagement of the lugs d' and f' and will compress the spring against the left-hand sleeve F, and 50 55 when the pressure on the drawbar is released the spring will return the saddle and drawbar to their central positions.
- In the construction described, the spring is inclosed and protected and does not project beyond the ends of the housing b', and since the sliding sleeves or parts which compress the springs are separate from the saddle and so connected thereto as to permit the saddle to move in each direction independently of, or relative to, one of the

sleeves, no part of the centering mechanism moves outwardly beyond the upright end parts of the carry-iron which determine the extent of movement of the saddle. Nevertheless the spring D can be and preferably 70 is substantially as long as the distance between the upright end parts of the carry-iron. In other words, with a saddle adapted to move from one to the other of the upright end walls of the carry-iron and a 75 spring extending from one to the other of said end walls, no part of the centering mechanism projects materially beyond or moves in operation outwardly beyond such end walls.

I claim as my invention:

1. The combination of a drawbar carry-iron having a hollow horizontal portion which forms a spring housing, a drawbar saddle arranged to slide on said housing, 85 abutments arranged to slide toward and from each other in said housing, a spring in said housing which extends substantially from end to end of the housing and normally holds said abutments yieldingly apart 90 in the opposite ends of said housing, said saddle being movable relative to both of said abutments and having a part adapted to move one of said abutments when the saddle is moved in one direction and a part adapted 95 to move the other abutment when the saddle is moved in the opposite direction, said abutments and spring in the normal position thereof extending outwardly beyond the opposite ends of said saddle.

2. The combination of a drawbar carry-iron having end attaching portions and a horizontal connecting portion, a drawbar saddle which is of less length than the distance between said attaching portions and is 105 adapted to slide on said horizontal portion of the carry-iron from one to the other of said attaching portions, abutments arranged to slide toward and from each other on said horizontal portion of the carry-iron, a 110 spring which normally holds said abutments yieldingly apart, said saddle being movable relative to both of said abutments and having a part adapted to move one of said abutments when the saddle is moved in one direction and a part adapted to move the other abutment when the saddle is moved in the opposite direction, said abutments and spring in the normal position of the abutments extending outwardly beyond the 115 opposite ends of said saddle.

3. The combination of a drawbar carry-iron having end attaching portions and a hollow horizontal portion which connects said attaching portions and forms a spring 125 housing, a drawbar saddle which is of less length than the distance between said attaching portions and is adapted to slide on said housing from one to the other of said attaching portions, abutments arranged to 130

slide toward and from each other in said housing, a spring in said housing which extends substantially from one to the other of said attaching portions of the carry-iron and 5 normally holds said abutments yieldingly apart with the outer ends of said abutments substantially in the vertical planes of said attaching portions of the carry-iron, said saddle being movable relative to both of said 10 abutments and having a part adapted to move one of said abutments when the saddle is moved in one direction and a part adapted to move the other abutment when the saddle is moved in the opposite direction. 15

4. The combination of a drawbar carry-iron having a hollow horizontal portion which forms a spring housing, a drawbar saddle arranged to slide on said housing, 20 sleeves arranged to slide toward and from each other in said housing, a spring which is arranged with its opposite ends extending into said sleeves and normally holds said sleeves yieldingly apart in the opposite ends 25 of said housing with the outer ends of said sleeves and the ends of the spring projecting outwardly beyond the opposite ends of said saddle, said saddle being movable relative to both of said sleeves and having a 30 part adapted to move one of said sleeves when the saddle is moved in one direction and a part adapted to move the other sleeve when the saddle is moved in the opposite direction.

35 5. The combination of a drawbar carry-iron having a tubular horizontal portion

which forms a spring housing and has open ends and a longitudinal slot, a drawbar saddle which is arranged to slide on said housing, abutments arranged to slide in the opposite end portions of said housing, engaging parts on said saddle and said abutments extending through said slot in the housing whereby said abutments are adapted to be moved by said saddle, a spring in said housing extending from one abutment to the other for yieldingly resisting the inward movement of said abutments, caps closing the ends of said housing, and a stationary securing bolt for said caps which extends 40 through said housing, abutments and spring. 45

6. The combination of a drawbar carry-iron having a tubular horizontal portion which forms a spring housing and has a longitudinal slot, a drawbar saddle which is arranged to slide on said housing, abutments arranged to slide in the opposite end portions of said housing, engaging parts on said saddle and said abutments extending through said slot in the housing whereby 50 said abutments are adapted to be moved by said saddle, said engaging parts having contacting undercut faces, and spring means in said housing for yieldingly resisting the inward movement of said abutments. 55

Witness my hand, this 15th day of March, 1916.

WILLARD F. RICHARDS.
